[57] CLAIM

The ornamental design for a telephone apparatus, substantially as shown and described.

DESCRIPTION

FIG. 1 is a top front perspective view of a telephone apparatus wherein the invention is embodied in a telephone set showing my new design;

FIG. 2 is a top front perspective view of a telephone with the handset lifted above the base showing my new design;

FIG. 3 is a top plan view thereof;

FIG. 4 is a front elevation thereof;

FIG. 5 is an end elevation thereof;

FIG. 6 is an elevation as seen from the opposite end of FIG. 5;

FIG. 7 is a bottom plan view thereof;

FIG. 8 is a side elevation of the handset separately shown for clarity of illustration;

FIG. 9 is a bottom plan view thereof;

FIG. 10 is an end elevation thereof, the undisclosed opposite end being a mirror image of the end portion shown except for the absence of the cord egress hole;

FIG. 11 is a top front perspective view of a second embodiment thereof with the handset lifted above the base wherein the invention is embodied in a telephone housing; and

FIG. 12 is a front elevation of the second embodiment thereof, the other views of which correspond to the views of the first embodiment except as the absence of features in the central portion of the telephone base.
